UNITED STATES PATENT OFFICE.

WILLIAM H. KOEHLER, OF JACKSON, MICHIGAN.

TRAFFIC-SIGNAL FOR MOTOR-VEHICLES.

1,291,928.

Specification of Letters Patent.

Patented Jan. 21, 1919.

Application filed August 7, 1917. Serial No. 184,924.

To all whom it may concern:

Be it known that I, WILLIAM H. KOEHLER, a citizen of the United States, residing at Jackson, in the county of Jackson and State 5 of Michigan, have invented certain new and useful Improvements in Traffic-Signals for Motor-Vehicles, of which the following is a specification.

This invention relates to an improved 10 traffic signal for motor vehicles and has as its primary object to provide a device of this character whereby a driver may indicate to a driver following an intention to turn to the right or left, to slow down or 15 stop.

The invention has as a further object to provide a device of this character which may be manually operated from the driver's seat and may thus always be easily controlled by the driver.

A still further object of the invention is to provide a signaling device which at night will normally display a red tail light and which will also act to illuminate the license 25 tag of the vehicle.

And the invention has as a still further object to provide a signaling device employing a character cylinder having different characters of traffic indicia stenciled there- 30 through for displaying different signals and wherein when any one of the said characters is arranged in position for display, another of the said characters will be disposed in position to provide a window through which 35 the light from within the character cylinder may shine against the license tag for illuminating the said tag.

Other and incidental objects will appear as the description proceeds and in the drawings wherein I have illustrated the preferred embodiment of the invention and wherein similar reference characters designate corresponding parts throughout the several views:

Figure 1 is a perspective view of my improved traffic signal particularly illustrating the operating lever employed for controlling the said signal and the arrangement of the cable between the shaft of the said 45 lever and the signal.

Fig. 2 is a bottom plan view of the signal,

Fig. 3 is a fragmentary sectional view particularly illustrating the mounting of the character cylinder employed,

Fig. 4 is a transverse sectional view taken on the line 4—4 of Fig. 3 and looking in the

direction of the arrows, this view particularly illustrating the disposition of the background pane for the character cylinder as well as the arrangement of the rear window 60 of the signal for illuminating the license tag,

Fig. 5 is a fragmentary sectional view taken on the line 5—5 of Fig. 3 and looking in the direction of the arrows, this view 65 illustrating the arrangement of the cable for actuating the character cylinder,

Fig. 6 is a plan view showing the blank from which the body of the character cylinder is formed and illustrating the traffic 70 characters stenciled in said cylinder body,

Fig. 7 is a fragmentary perspective view showing one of the end plates of the supporting frame for the background pane,

Fig. 8 is a plan view of one of the lamp 75 sockets employed, and

Fig. 9 is a detail perspective view particularly illustrating the mounting of the pulleys over which the actuating cable for the character cylinder is trained.

In carrying out the invention I employ a cylindrical casing 10 provided at the forward side thereof, as particularly shown in Fig. 4, with a longitudinally extending window opening closed by a glass pane 11. Securing the pane in position are strips 12 engaging the side margins of the pane. Connected to the casing adjacent its extremities are supporting brackets 13 secured in position by rivets or other suitable fastening devices and extending beneath the casing, as also particularly shown in Fig. 4, to provide hangers therefor. The rear portions of these brackets are, as illustrated in detail in Fig. 2, provided with lateral flanges 14 by which the signaling device may be secured upon the rear of a motor vehicle at some suitable point below the license tag and, for convenience, such a tag has been conventionally illustrated at 15 in Fig. 4 of the drawings. Formed in the upper rear side of the casing is a longitudinally extending window opening closed by a glass pane 16. This pane is preferably arranged tangentially to the axis of the casing and at one margin of the said pane, the wall of the casing is bent up, as illustrated at 17, to support the pane in position. Connecting the pane with the casing are suitable strips 18.

Removably fitting over one end of the 110 casing 10 is a closure cap 19 and removably fitting over the opposite end of the said

casing is a similar closure cap 20. These closure caps are pressed in centrally to provide annular flanges 21 and 22 respectively, arranged concentric to the axis of the casing. 5 Detachably connecting the closure caps and extending horizontally through the casing are spaced parallel rods 23. This provides an arrangement whereby the closure caps for the casing will be firmly held in position to 10 exclude practically all dust and dirt therefrom.

Rotatably mounted within the casing is a character cylinder or drum 24 the body of which is formed from a blank as shown in 15 detail in Fig. 6 of the drawings. This blank is preferably constructed from a piece of suitable sheet metal secured together at its ends to provide the drum body. Stenciled through the blank adjacent one end thereof 20 is the representation of an arrow 25 pointing toward the left and providing a left turn signal. Stenciled through the blank in spaced relation to the arrow 25 is a second arrow 26 pointing toward the right and providing a right turn signal. The blank is 25 further provided with a stencil defining the word Slow and a stencil defining the word Stop. Formed through the blank between the arrows 25 and 26 is a window opening 30 closed by a pane of red glass 27. It will now be seen that when the ends of the blank are connected to form the drum body, as previously described, the several traffic signals of the blank will be arranged at circumferentially spaced points about the drum body. 35 Snugly fitting over the ends of the drum body are caps 28 and 29 respectively. The cap 28 is formed centrally with an inwardly directed annular flange 30 rotatably surrounding the 40 flange 22 of the end cap 20 of the casing. The end cap 29 of the drum is formed centrally with an outwardly directed annular flange 31 rotatably surrounding the flange 21 of the end cap 19 of the casing. 45 The flanges 30 and 31 will thus rotatably support the character drum within the casing. At its outer edge the flange 31 of the end cap 29 is formed with an annular radial lip 32.

50 Mounted upon the connecting rods 23 is a frame supporting a background pane for the stencils of the character drum 24. This frame includes end plates 33 provided with spaced legs 34 having the rods 23 fitted therethrough. The end plates 33 are mounted within the character drum 24 adjacent the end caps 19 and 20 of the casing and interposed between the said end caps and the legs of the said plates are spacing sleeves 35 55 surrounding the said rods. Connecting the end plates 33 are spaced parallel channel strips 36 and fitted at its side edges within these strips is a curved translucent background pane 37 which is preferably formed 60 of white or opal glass. The upper edges of 65

the end plates 33 are curved to conform to the curvature of the pane 37 and struck from the said edges of the plates are a plurality of staggered lugs 38 engaging over and beneath the ends of the pane. These lugs will 70 thus coöperate with the channel strips 36 for rigidly supporting the pane 37 in position adjacent the inner face of the body of the drum 24 and opposite the front pane 11 of the casing. The pane 37 will thus form a 75 white background immediately in the rear of the stencils of the character drum and in this connection, it should be stated that in order to enhance the relief of the said stencils the outer surface of the drum body is preferably 80 painted or otherwise coated black.

Mounted upon the end caps 19 and 20 of the casing to project longitudinally within the character drum are complemental lamp brackets 39. These lamp brackets are preferably formed of suitable sheet metal and at their inner extremities are provided with lateral lugs or wings 40 riveted or otherwise secured to the end caps of the casing. At the outer extremities of the brackets, the metal 90 thereof is bent to provide cylindrical sockets 41 in which are removably fitted electric lamps conventionally illustrated at 42. Arranged in the rear of the lamps 42 are reflectors 43 having arms 44 extending therefrom and surrounding the lamp sockets for supporting the reflectors in position. As shown in Fig. 4 of the drawings, the lamps 42 are arranged adjacent the rear side of the casing opposite the front pane 11 and in a 100 plane almost directly below the upper pane 16 of the casing. Furthermore, it will be noted that the reflectors 43 are so arranged that the said reflectors will not cut off the light rays from the pane 16. Fitted through the end caps 19 and 20 of the casing are insulating sleeves 45 through which are fitted circuit wires 46. These circuit wires are, as particularly shown in Fig. 3 of the drawings, led through suitable openings in the 110 brackets 39 into the sockets 41 for supplying current to the lamps 42. The wires 46 may, of course, be connected with any suitable source of electrical energy upon the vehicle 115 equipped with my improved device.

Supported by the end cap 19 of the casing at the lower rear side thereof are spaced pulleys 47. These pulleys are rotatably mounted upon bolts or trunnions 48 extending from a plate 49 resting within the casing 120 and confronting the end cap 29 of the character drum. Formed on the lower edge of the plate is a suitable lateral flange secured to the casing for supporting the plate in position. At their outer extremities the trunnions 48 are removably fitted through the end cap 19 and detachably connected thereto by nuts at the outer ends of the said trunnions. This provides an arrangement whereby the pulleys will be 125 130

- rigidly supported in position and may be detached when the end cap is removed. Led through a suitable opening in the casing 10 between the pulleys 47 is a cable 50 which is wrapped one or more times about the flange 31 of the end cap 29 of the character drum. The purpose of the lip 22 upon the said flange will now become apparent since it will be seen that this lip will 5 retain the overlapping strands of the cable in position upon the said flange. The cable 50 is trained over one or more pulleys 51 and is carried to the front of the vehicle to be wrapped one or more times about a pulley 52 upon the lower end of an actuating shaft 53. The shaft 53 may be rotatably mounted upon the vehicle in any approved manner and the upper end of the shaft is arranged to terminate at some point 10 convenient to the driver's seat of the vehicle as, for instance, at the vehicle instrument board. Mounted at the upper extremity of the said shaft is a fixed dial plate 54 and connected to the adjacent terminal of the shaft to move over the said plate is an actuating lever 55. The plate 54 at suitable circumferentially spaced points is provided with suitable notches or marks respectively identified by the letters 15 S indicating stop, L indicating left, N indicating neutral, R indicating right, and S1 indicating slow. At the notch indicated as stop, is arranged a pin 56 upon the dial for limiting the lever 55 in its movement in 20 one direction and at the notch indicated as slow is arranged a second pin 57 for limiting the lever in its movement in the opposite direction.
- The pulley 52 of the shaft 53 is, of course, 25 so connected with the character drum 24 by the cable 50 that when the lever 55 is moved into register with any one of the notches in the dial plate, the character drum will be rotated to display a corresponding traffic signal opposite the front pane 11 of the casing of the device. Consequently, by manipulating the lever 55 the driver may readily indicate to the driver following an intention to turn either to the right or left, to 30 slow down or stop and owing to the provision of the white background pane 37, the signal displayed may be easily observed. Normally, the lever 55 will be arranged at the notch indicated as neutral upon the dial plate 54 when the red glass pane 27 of the character drum will be disposed opposite the front pane 11 of the casing. Thus, in the day time, no signal will be displayed when the vehicle is pursuing a given course while 35 at night, when the lamps 42 are energized, the red glass pane 27 will cause the normal display of a red tail light. On the other hand, when the character drum 24 is rotated to bring any one of the traffic signals opposite the front pane 11 of the casing, the
- lamps 42 will, of course, illuminate such signal so that it may be easily observed. In this connection attention is now directed to the fact that the traffic signals are so arranged about the character drum 24 that 40 when any one of the said signals is brought opposite the front pane 11 of the casing for display, another of the said signals will be disposed between the lamps 42 and the top pane 16 of the casing. Such latter signal 45 will, when so disposed, thus provide a window through the character drum through which the rays from the lamps may shine against the license tag 15. Consequently, this tag will, at night, always be illuminated 50 without regard to the operation of the character drum to display any particular traffic signal.
- It will therefore be seen that I provide a particularly simple and efficient construction for the purpose set forth and a device which may be employed in connection with substantially any conventional type of motor vehicle. Furthermore, the device is 55 compact and of such structural nature that 60 it may be manufactured at minimum cost.
- Having thus described the invention, what is claimed as new is:
1. A device of the character described including a casing, end caps for the casing, the said end caps being pressed in centrally to provide annular flanges, a character drum rotatably mounted within the casing upon the said flanges and provided with a plurality of traffic signals, and means for adjustably rotating the said drum for selectively moving the said signals into position for display. 65
  2. A device of the character described including a casing, end caps therefor, means extending between and connecting the said caps, a character drum rotatably mounted within the casing and having a plurality of traffic signals exposed through the drum, an element mounted upon said means within 70 the drum and providing a background for the said signals, and means for adjustably rotating the said drum for selectively moving the said signals into position for display. 75
  3. A device of the character described including a casing, a character drum rotatably mounted within the casing and having a plurality of traffic signals adapted to be exposed through the casing, a stationary translucent background pane for the said signals 80 arranged within the drum, and means for rotating the drum for selectively moving the said signals into position for display in front of said pane. 85
  4. A device of the character described including a casing, rods extending through the casing, a character drum rotatably mounted within the casing and having a plurality of traffic signals exposed through the drum, a frame mounted upon said rods 90

within the drum, an element carried by the said frame and providing a background for the said signals, and means for adjustably rotating the said drum for selectively moving the said signals into position for display.

5. A device of the character described including a casing, end caps therefor, means extending between the said caps and securing the said caps in position, a character drum rotatably mounted within the casing and having a plurality of traffic signals exposed through the drum, a frame mounted upon said means, a background pane for the signals mounted upon the said frame within the drum, and means for adjustably rotating the said drum for selectively moving the said signals into position for display.

6. A device of the character described including a casing, end caps therefor, means securing said caps in position, a character drum rotatably mounted within the casing and having a plurality of traffic signals exposed through the drum, a frame mounted upon said means within the drum and including end plates connected to the said means and channel strips connecting the said plates, a background pane for the said signals received at its side margins within said strips and supported by the frame within the drum, and means for adjustably rotating the said drum for selectively moving the said signals into position for display.

7. A device of the character described including a casing, end caps for the casing provided with flanges, a character drum arranged within the casing and including end caps provided with openings receiving the flanges of the end caps of the casing and having flanges surrounding said openings and coöperating with said first mentioned flanges for rotatably supporting the drum thereon, the said character drum being provided with a plurality of traffic signals, and means for adjustably rotating the said drum for selectively moving the said signals into position for display.

8. A device of the character described in-

cluding a casing, end caps therefor, a character drum arranged within the casing, means at opposite ends of the drum rotatably supporting the drum upon the said end caps, the drum being provided with a plurality of traffic signals, and means engaging the said first mentioned means at one end of the drum for adjustably rotating the said drum to selectively dispose the said signals into position for display.

9. A device of the character described including a casing, end caps therefor, a character drum arranged within the casing and including end caps provided with flanges rotatably supporting the drum, the drum being provided with a plurality of traffic signals, and means engaging the flange of one of said end caps of the drum for adjustably rotating the drum to selectively dispose the said signals in position for display.

10. A device of the character described including a casing, end caps therefor, a character drum rotatably mounted within the casing upon the said caps, spaced pulleys supported by one of said caps within the casing, the said drum being provided with a plurality of traffic signals, and a flexible element engaged with one end of the drum and trained between said pulleys for adjustably rotating the drum to selectively dispose the signals in position for display.

11. A device of the character described including a casing, end caps therefor, means securing said caps in position, a character drum rotatably mounted within the casing and having traffic signals exposed through the drum, end plates supported by the said means within the drum, lugs carried by the said end plates, a background pane for the signals engaged at its ends by the said lugs and supported by the plates within the drum, and means for adjustably rotating the drum for selectively moving the said signals into position for display.

In testimony whereof I affix my signature.

WILLIAM H. KOEHLER. [L. S.]
